UNITED STATES PATENT OFFICE.

THOMAS H. DONNELLY, OF DOVER, NEW HAMPSHIRE, ASSIGNOR TO CROMPTON & KNOWLES LOOM WORKS, OF WORCESTER, MASSACHUSETTS, A CORPORATION OF MASSACHUSETTS.

TOOL FOR KNOWLES LOOMS.

Application filed April 29, 1926. Serial No. 105,598.

This invention relates to a tool to facilitate the repair of harness and pattern mechanisms more particularly of the type set forth in patent to Knowles No. 186,530, and it is the principal object of the invention to provide a device simple in construction and operation which shall be effective to hold the vibrator levers and connectors of pattern mechanisms of the type specified in such position as will permit the ready removal of the comb which separates the vibrator levers.

The so-called Knowles head comprises a pair of spaced positively rotating mutilated cylinder gears between which lie a plurality of thin vibrator gears each of which is mounted on a vibrator lever. These levers are separated by means of a comb fixed to the frame of the head and it sometimes happens that the dents of the comb become broken, in which event a new comb must be supplied. It is necessary under such circumstances to hold all of the vibrator levers in raised position where they will not interfere with the removal of a broken comb and the replacing of a new one and it is usual practice for loom fixers either to block up the vibrator levers or to remove them from the loom. This has been found to be a time-consuming operation and it is a more particular object of my invention to provide a bar which is passed under some part of the vibrator lever or gear and supported so as to hold the vibrator levers in raised position.

With these and other objects in view which will appear as the description proceeds, my invention resides in the combination and arrangement of parts hereinafter described and set forth in the claims.

In the accompanying drawings wherein I have shown a convenient embodiment of my invention.

Fig. 1 is a front elevation of a Knowles head having the top cylinder removed and with my invention applied thereto,

Fig. 2 is a vertical section on line 2—2 of Fig. 1 looking in the direction of the arrows toward the comb, and

Fig. 3 is a perspective view of the tool.

Fig. 4 is an elevation view, partly sectional, of the tool.

Referring to the drawings it will be seen that I have shown a loom frame 10 having

arches 11 to which is secured a head frame 55 12. Said frame is provided with upper and lower cross bars 13 and 14, respectively, and supports on the outer end thereof a heel pin 15. Mounted for limited movement on the heel pin is a plurality of vibrator levers 16 60 which extend inwardly from the heel pin and have rotatably mounted thereon vibrator gears 17. Each of said gears is provided with an arcuate slot 18 concentric with the stud 19 about which it rotates and there is further pivoted to each vibrator gear as at 20 a harness connector 21 which is attached to a harness jack 22 operatively connected to the harness (not shown) of the loom. 70

In order to hold the connectors 21 down there is pivoted to the head frame as at 23 a plurality of drop weight levers one of which is indicated at 24 in Fig. 1. Each of said levers is engaged by a spring pressed 75 plunger 25 held in a frame 26 secured to the arches of the loom.

A lock knife 27 is pivoted as at 28 to a fixed part of the loom frame and moves toward and from the end 29 of the vibrator 80 lever 16 by well-known mechanism not shown, being moved away to permit uninterrupted movement of said levers as the same are raised by pattern mechanism indicated at 30. Each of said ends 29 of the 85 vibrator levers is guided by a comb 31 the dents 32 of which are shown more particularly in Fig. 2. Said comb is provided with depending arms 33 which may be secured as at 34 to the lower cross bar 14 of the head 90 frame.

In order to actuate the gears 17 there are usually provided a pair of actuating cylinders which fit in upper and lower bearings 35 and 36, respectively, the lower cylinder 95 37 being shown and the upper one being removed. Under normal conditions the vibrator gears are raised and lowered by the pattern mechanism 30 to be actuated by the upper and lower cylinder gears according to 100 the requirements of the pattern or weave. The matter thus far described is the usual form of Knowles head.

It occasionally happens that the comb 31 will become broken or rendered useless, in which case it must be replaced and in this event I provide a tool 50 which can be employed for raising all of the vibrator levers 105

16. As shown in the drawings said tool comprises upper and lower bars 51 and 52, respectively, which are sufficiently long to extend beyond the front and back portions 5 of the head frame 12 as shown in Fig. 2. The upper cylinder is removed and the lower part of the bearing therefor receives the upper bar 51. Located at each end of the bar is a loop or strap member 53 through 10 which both bars extend and in the upper part of which is threaded a thumb screw 54 which extends into the opening 55 and presses against the top of rod 51.

The harness jacks are all moved to lower 15 the harness frames so that the arcuate slots 18 of the vibrator gears 17 are on the left hand side as shown in Fig. 1 and rod 52 is then passed through the upper portion of the arcuate slots and screws 54 tightened to 20 raise the rod 52 and ends 29 of the vibrator levers 16 sufficiently to permit convenient removal of the comb 31. The rod 52 will hold the vibrator gears in raised position without further attention on the part of the 25 operator and if desired the screw 54 can be turned to lower the ends 29 slightly so as to position the dents 32 of the new comb.

The straps 53 can be slid along bars 51 and 52 to permit the tool to be used with 30 heads of different widths and said bars are interchangeable, either bar being adapted to cooperate with the vibrator gears or with the bottom half of bearing 35. I do not wish to be limited to the particular means 35 shown for supporting the lower rod nor to any particular part of the vibrator and gear which is to be in direct engagement with the lower rod.

From the foregoing it will be seen that 40 I have provided a very simple device for holding the vibrator gears of the well-known Knowles head in raised position to facilitate the replacement of the comb, the use of the device rendering removal of the 45 vibrator gears from the head unnecessary. It will further be seen that the drop weight levers 24, the normal function of which is to hold the connectors 21 down, will serve to prevent accidental upward displacement of the rods 51 and 52 before the vibrator gears have been raised to their highest position. For this reason an operator can leave the 50 loom with the vibrator gears not fully raised and said drop weights would serve to hold them against accidental displacement.

Having thus described my invention it will be apparent that changes and modifications may be made therein by those skilled in the art without departing from the spirit 60 and scope of the invention, and I do not wish to be limited to the details herein disclosed, but what I claim is:

1. A tool for use with a loom pattern mechanism having bearings in the upper portion thereof for a cylinder, a plurality 65 of vibrator levers and vibrator gears therefor each provided with an arcuate slot and having also a comb for spacing the vibrator gears, said tool comprising a pair of spaced rods one of which is received in the bearing and the other of which passes through the arcuate slots in the vibrator gears, and means supported by the rod in the bearing to hold the bar passing through the gears and the gears supported thereby in raised 75 position.

2. A tool for use with a loom pattern mechanism having bearings in the upper portion thereof for a cylinder, a plurality 80 of vibrator levers and vibrator gears therefor each provided with an arcuate slot and having also a comb for spacing the vibrator gears, said tool comprising a pair of spaced rods one of which is received in the bearing and the other of which passes through the arcuate slots in the vibrator gears, and means supported by the rod in the bearing 85 to raise and hold the bar passing through the gears and the gears supported thereby in raised position.

3. A tool for use with a loom pattern mechanism having bearings in the upper portion thereof for a cylinder, a plurality 90 of vibrator levers and vibrator gears therefor each provided with an arcuate slot and having also a comb for spacing the vibrator gears, said tool having a member to be received by the bearing and having a second member to pass through the aligned arcuate 95 slots of the gears, and elements surrounding 100 said members and supported by the upper member, whereby the said upper member supports the lower member and the gears held thereby.

4. A tool for use with a loom pattern mechanism having bearings in the upper portion thereof for a cylinder, a plurality 105 of vibrator levers and vibrator gears therefor each provided with an arcuate slot and having also a comb for spacing the vibrator gears, a pair of spaced rods one of which is received by the bearing and the other of which passes through the aligned slots of the vibrator gears, hollow holding members 110 for the ends of the rods surrounding the latter, and a screw passing through said holding members into the hollow portions thereof to engage one of the rods and effect relative movement thereof with respect to the other rod.

In testimony whereof I have hereunto affixed my signature.

THOMAS H. DONNELLY.
